UNITED STATES PATENT OFFICE.

AUGUST L. F. HOLZERLAND, OF BUFFALO, NEW YORK.

RADIATOR FOR AUTOMOBILES.

No. 892,832.

Specification of Letters Patent.

Patented July 7, 1908.

Application filed September 10, 1906. Serial No. 333,978.

To all whom it may concern:

Be it known that I, AUGUST L. F. HOLZERLAND, a citizen of the United States, residing at Buffalo, in the county of Erie and State of New York, have invented certain new and useful Improvements in Radiators for Automobiles and the Like, of which the following is a specification.

My invention relates to radiators used on automobiles for cooling the circulating fluid passing around the engine cylinder, and more particularly to that class of radiators provided with fluid-tubes separated by air-spaces and having an inlet-chamber and an outlet-chamber common to all tubes.

The primary object of my invention is the production of a simple, durable, and inexpensive radiator with which the maximum cooling efficiency is obtained.

Other objects are to so construct the fluid-tubes that the cooling-fluid is compelled to travel through a circuitous course in short right angular stretches; to provide for the equal distribution of the cooling-fluid through the various fluid-tubes; and to otherwise improve on radiators of the type mentioned.

With these objects in view the invention consists in the construction, arrangement, combination of parts to be hereinafter described, and particularly pointed out in the subjoined claims.

In the drawings,—Figure 1 is a front elevation of a radiator embodying my invention. Fig. 2 is a vertical longitudinal section taken through the upper portion of the inlet-chamber. Fig. 3 is an enlarged horizontal section taken on line 3—3, Fig. 2. Fig. 4 is a vertical section taken on line 4—4, Fig. 3.

Fig. 5 is an enlarged front elevation of a portion of several of the fluid-tubes. Fig. 6 is an enlarged vertical section through a portion of several of the fluid-tubes. Fig. 7 is a horizontal section taken on line 7—7, Fig. 5. Fig. 8 is a perspective view of a portion of one of the fluid-tubes.

Referring to the drawings in detail, like letters of reference refer to like parts in the several figures.

A designates the casing having at its upper end an inlet-chamber B provided with an inlet pipe b; and at its lower end an outlet-chamber C provided with an outlet-pipe c. Connecting said chambers are the fluid-tubes

D, each constructed of thin sheet copper or similar material with the upper and lower ends thereof opening into the inlet-chamber and outlet-chamber, respectively. Each of said tubes has a plurality of transverse channels E, which are formed by bending the tube at regular intervals in substantially U-shaped form; thus providing short parallel stretches F lying in two different vertical planes and connected by short connecting stretches G arranged at right angles to said parallel stretches. By this arrangement, the flow of water through the tubes is slightly retarded. By arranging the stretches G at right angles to the parallel stretches F, sharp angles are formed which offer a resistance to the free flow of the fluid, and greatly increase the cooling efficiency of the radiator.

As best shown in Figs. 5 to 8, one-half of the short vertical stretches F of the tubes have protuberances f in the form of teats punched in the outer walls thereof which bear against the adjacent vertical stretches of adjoining tubes. In this manner a narrow air-passage is provided between adjacent vertical stretches for the purpose of increasing the radiating surface. The tubes are arranged with the channels E of adjoining tubes opposing each other whereby rectangular air-passages H are formed which are arranged in a series of horizontal rows with the passages of alternate rows in vertical alignment. As is common in fluid-tubes of this type, one or both walls of the tubes is provided with numerous teats or protuberances I, which serve to maintain the walls of each tube in separated condition, and provide unrestricted fluid-passages.

Difficulty has been experienced in traveling over uneven roads in respect to the distribution of the cooling fluid to the various fluid-passages. When the radiator is not in a perfectly horizontal plane, the cooling fluid is ordinarily directed to the inclined or lowered side of the radiator. To obviate this, I provide within the inlet-pipe b, a separator-partition J which divides the said pipe at the inner end thereof into chambers K and L; said partition extending preferably into the inlet-chamber of the radiator. Within said chamber is a fluid-receiver M in the form of a perforated V-shaped trough which is inclined toward opposite sides of the inlet-chamber. The cooling fluid passing through said inlet-

pipe is divided into two flowing bodies which enter the fluid-receiver and flow in opposite directions in equal quantities. In this manner the fluid is distributed equally to all fluid-
5 passages.

Having thus described my invention, what I claim is,—

1. In a radiator for automobiles and the like, the combination with the inlet-chamber 10 having an inlet-pipe, an outlet-chamber having an outlet-pipe, and fluid-passages connecting said chambers, of a fluid-receiver within the inlet-chamber and inclined in opposite directions from said inlet-pipe.
- 15 2. In a radiator for automobiles and the like, the combination with the inlet-chamber having an inlet-pipe, an outlet-chamber having an outlet-pipe, and fluid-passages connecting said chambers, of a fluid-receiver 20 within the inlet-chamber and inclined in opposite directions from said inlet-pipe, and a separator-partition in said inlet-pipe to divide the fluid into two flowing bodies enter-

ing the fluid-receiver on opposite sides of the said partition.

3. A radiator of the class described comprising an inlet-chamber, an outlet-chamber, and a series of vertically disposed fluid-tubes connecting said chambers, said tubes being provided with short parallel horizontal 30 stretches connected by vertical stretches somewhat longer than said horizontal stretches to form transverse channels having right-angled walls, the channels of adjoining tubes being opposed to provide rectangular 35 transverse air-passages and one of each of the adjacent vertical stretches of adjoining tubes having teats thereon to provide narrow air-passages.

In testimony whereof, I have affixed my 40 signature in the presence of two subscribing witnesses.

AUGUST L. F. HOLZERLAND.
